UNITED STATES PATENT OFFICE.

OSCAR WILLIAM BERGMAN, OF OSKAR FREDERICKSBORG, NEAR WAXHOLM,
SWEDEN.

FIRE-ARM.

SPECIFICATION forming part of Letters Patent No. 430,614, dated June 24, 1890.

Application filed January 2, 1889. Serial No. 295,180. (No model.) Patented in Sweden April 7, 1888, No. 1,601.

To all whom it may concern.

Be it known that I, OSCAR WILLIAM BERGMAN, a subject of the King of Sweden, residing at Oskar Fredericksborg, near Waxholm, Sweden, have invented new and useful Improvements in Fire-Arms, (patented in Sweden April 7, 1888, No. 1,601,) of which the following is a specification.

My invention relates to fire-arms, and comprises the improvements hereinafter described.

In order to enable the invention to be fully understood, I will describe how it can be carried into practice by reference to the accompanying drawings, in which—

Figure 1 is a right-hand side elevation of a rifle or arm constructed according to my invention. Fig. 2 is a longitudinal section of the mechanism loaded with four cartridges; Fig. 3, a cross-section in the line 7 8 of Fig. 8. Figs. 4, 5, and 6 are cross-sections of the mechanism in the lines 1 2, 3 4, and 5 6, respectively, of Figs. 2 and 8; Fig. 7, a cross-section of the box through the lines 9 10 of Fig. 8. Fig. 8 is a top view of the box containing the mechanism. Fig. 9 shows a longitudinal section, and Fig. 9^A a plan, of the bolt; and Figs. 9^B and 9^C are cross-sections of the same in the lines 11 12 and 13 14, respectively. Fig. 10 is a view of the rear end of the bolt turned upward and viewed from below. Fig. 11 shows the firing or striking pin in longitudinal section, and Figs. 11^A and 11^B are respectively cross-sections of the same. Fig. 12 shows the rear support of the mainspring in longitudinal and cross sections, and Fig. 13 illustrates the closing-pin of the bolt in side view and in end view. Fig. 14 illustrates a loose part of the same in side and end views, respectively. Fig. 15 illustrates the extractor in side and plan views. Fig. 16 illustrates the extractor-spring in side and plan views. Fig. 17 is a view of the magazine loaded with one cartridge. Fig. 18 illustrates two views of the safety-stopper, one on the gun and one detached.

The breech mechanism is inclosed in a box *a*, secured upon the rear end of the barrel. The box is bored centrally to a diameter some-what wider than the flange of the cartridge

intended for the rifle. In the top the box has a segmental slot *d*, which at its fore part is enlarged toward the right-hand side at *e* to somewhat more than double the width. In the bore of the box moves the cylindrical bolt *b*, provided with a segmental shoulder *c*, adapted to the slot *d* in the box, and guiding in this way the bolt when moving alternately in the direction of the axis of the barrel. The length of this shoulder *c* is such that when the bolt is advanced and turned to the right it falls into and fills the recess *e* in the box. The rear side of the recess *e* is beveled in order that the shoulder *c* may, when rotating the mechanism, be forced forward, and thus by means of the bolt force the cartridge home. When firing, the shoulder *c* receives the recoil. The bolt being turned to the left, the cartridge is loosened by the extractor and the shoulder *c* is brought slightly backward and slides against a beveled surface *j*, arranged in the fore part of the recess *d*.

Motion is imparted to the bolt by means of a lever *f*, firmly fixed to the same and clasping its rear end. The mechanism being closed, this lever is turned downward, clasping the neck of the butt-end, and forming at its lower part a gripper situated immediately behind the guard, in which gripper the little finger, the ring-finger, and the middle finger of the right hand rest, while the thumb clasps the neck of the butt and the forefinger enters the guard ahead of the trigger. By this arrangement the hand will never need to release its grip when reloading from the magazine. While keeping the rifle held to the shoulder the gripper *f* can be turned up by the right hand, the thumb resting against the rear top part of the gripper. The parts are then free to move backward and the mechanism will be thereby opened, the empty cartridge thrown out, and a new cartridge introduced from the magazine ahead of the piston. Immediately after the bolt has been brought back so far as permitted by the shoulder *Z* the gripper is again advanced and turned down, the bolt being then entirely introduced. By this motion the cartridge is brought home and the mechanism is closed at the same time that the right hand is brought back into a position

suitable for taking aim, after which the rifle can immediately be fired in the usual manner. These different motions upward, backward, forward, and downward are combined 5 in one single motion, during which the position of the rifle and the grasp of the hand need not be changed.

The piston or bolt *b* has a cylindrical bore *g* for the mainspring and the striker, and a 10 conical bore *h* in the fore part for the striker or striking-pin. The striker *i* is of cylindrical form, with a tongue *i'* behind, and a cylindrical piston *l* screwed to it near its point. Surrounding the cylindrical part of the striker 15 is a movable cylinder *k*, having a slot for receiving the tongue *i'* of the striker. Between the fore part of this cylinder and the rear part of the piston of the striker the spirally-coiled mainspring is inserted. The striker, 20 with piston *l*, cylinder *k*, and mainspring, is introduced from behind into the bore *g* of the bolt *b*, when the tongue *i'* of the striker enters a slot *m* in the under side of the bolt. This slot has at its front end an enlargement 25 *n*, Fig. 10, into which the tongue *i'* can move without following the bolt *b* when being turned. The lower edge of the tongue moves into a groove *o* in the bottom of the box *a* when the mechanism is advanced. When 30 turning up the bolt, the tongue is retained in this groove *o*, the beveled surface of the fore part of the recess *n* in the bolt *b* forces the bolt along. In this way the mainspring is compressed by degrees so long as the turning motion continues, after which the tongue of the striker is retained in its rear position 35 against the surface *p*, Fig. 10. This compression of the mainspring is effected in such a manner that the striker on its retrograde motion in the bolt will, by means of the piston 40 *l*, push the fore part of the mainspring backward. The back part of the mainspring then presses against the cylinder *k*, which in turn rests against the breech-pin *q*. This pin is of 45 cylindrical shape and provided with a key *r*. It is introduced from behind into the bore *g* of the bolt *b*, the key *r* entering the slot *m*, and after the pin *q* is turned it is retained by the mainspring and at the same time effects the 50 reaction of the mainspring against the bolt *b*. The compression of the mainspring is thus effected when turning up the lever *f*. At the backward and forward motion of the bolt *b* the tongue of the striker is retained against the 55 surface *p*, Fig. 10, by the pressure of the spring, but is released by turning down the lever. It is, however, prevented by the point *t* of the trigger from advancing until the trigger is actuated for firing. When the mechanism 60 is to be put in the safety position, (corresponding to half-cock,) the trigger is actuated while turning down the operating-lever, and in this way the point of the striker is during the turning movement caused to 65 advance by degrees toward the percussion-cap. Firing by accident cannot meanwhile occur, as the striker is completely inclosed in

the piston. Whenever the striker is to be cocked for firing, this is effected by turning the lever rapidly up and down but without bringing the bolt backward.

In order to obtain greater safety and to allow the marksman to see at a glance that the rifle is in the safety position, I provide a safety-stop *S*, located in the butt perpendicularly to and immediately below the upper part of the trigger *t*. The stop *S* has a recess *U*, in which the trigger *t* can enter when the handle *W* of the safety-stop is in its lowest position. If, on the contrary, the handle of the safety-stop be turned upward to an angle of sixty degrees, the said recess will be turned away, so that the trigger *t* cannot be pulled down, and the arm consequently cannot be fired.

The plate *u* serves to fill up the space in the slot behind the tongue *i'* of the striker. The top of the shoulder *c* is flat in front and provided with a screw-threaded pin *v*, the head of which is oval. On this flat part and 90 fixed to the shoulder by the pin *v* is the extractor-spring *x*. The extractor *w* is located in a slot in the fore part of the shoulder *c*, and is retained therein by the extractor-spring *x* and compelled to follow the motions 95 of the bolt *b* by means of a pin *w'*, upon which the extractor works, a cut being made in the extractor to receive the pin *w'*. The fixing of the extractor is effected after the bolt *b* has been partly introduced, but not turned 100 round, whereby the extractor *w* is placed in its slot, and the hole of the extractor-spring *x* is passed over the pin *v* on the bolt and the extractor turned a quarter of a revolution forward, when the spring takes into the 105 extractor.

The box *a* has in its lower part an opening *a'* to allow the cartridges from the magazine to pass through. This opening is longer than the cartridge, and is so arranged that the rear end of the cartridge cannot entirely pass through, only a part of the flange rising into the interior of the box when the bolt *b* in its backward motion has left a space for it. The cartridge-flange can thus be actuated by the bolt *b* in its forward motion, and consequently follow the same. The cartridge-flange having thus followed the rear and narrower part *o'* of the opening *a'* the cartridge, actuated by the magazine-spring, can now pass entirely 110 through the bottom of the box at the wider part of the opening *a'*, and thus completely rise ahead of the bolt *b*. The point of the cartridge (the bullet) has now mounted an inclined plane *A*. The cartridge, after being 115 entirely released from the magazine, is prevented from jumping out of the box by the flange getting under the tooth of the extractor and the point under the front top side of the box.

The extraction of the empty cartridge is effected by the extractor seizing the flange of the cartridge and by the backward motion of the latter. The empty cartridge is thrown 120

out through the opening *e* of the box by the lower part of the cartridge-flange being suddenly stopped against the flange of the cartridge jumping up from below, or in the case 5 of the last cartridge (after it has been fired) by its flange coming against a shoulder *B* on the cartridge-bed *C*.

The magazine *D* is made of a bent plate with a partition *E*. It is fixed on the rifle by means of two lugs *F*, clasping and engaging in a corresponding bevel on the box-shoulder *G*. The lugs of the magazine having been placed in this position the magazine is swung into the recess in the butt and is fixed by the bar *H*. Between the front rounded face of the box-shoulder *G* and the rear face of the partition *E* the cartridge-bed has a vertical motion. This motion is adapted to the conical shape of the cartridge, so that the top 15 surface of the cartridge-bed always corresponds with the generatrix of the truncated pyramid formed by the interior of the magazine. This is effected by means of two guide-bars *I* and *K*, of which the foremost *K* is formed by an extension *L* into a lever actuated by the magazine-spring *M*. This magazine, intended for 20 sporting-rifles, is filled by introducing the cartridges separately one by one into the same.

Having now particularly described and ascertained the nature of my said invention and 25 in what manner the same is to be performed, I declare that what I claim is—

1. In breech-loading rifles provided with bolt mechanism, the combination of the firing-pin *i*, its tongue *i'*, both inclosed in the 35 cylindrical bolt *b*, the cylinder *k*, surrounding the rear end of said pin, the mainspring acting against the rear end of said part *k*, as set forth, and the closing-pin *q* in the rear of the bolt *b*, the latter having a slot *m* in its under 40 side made with an enlargement having an inclined surface for the tongue *i'*, and also having a recess, in which the tongue of the firing-pin moves and is held after being cocked.

2. In a breech-loading rifle, the combination, with the rifle-cylinder *b* and with the operating-lever *f*, extending downward and clasping the neck of the butt, as described, of cartridge-magazine *D*, located in the center line of the rifle beneath the mechanism and 45 immediately ahead of the guard, and provided with a cartridge-bed *C*, movable therein and lifted by a guide-lever *K* and spring *M*, such lever bearing upward against the bed near its forward end, and the bed being further 50 guided in its vertical movement by a bar *I*, bearing against the end of said bed, all as 55 shown and described.

OSCAR WILLIAM BERGMAN.
